UNITED STATES PATENT OFFICE.

JOHN F. O'CONNOR, OF CHICAGO, ILLINOIS, ASSIGNEE TO WILLIAM H. MINER, OF CHAZY, NEW YORK.

DETACHABLE DRAW-BAR AND YOKE CONNECTION.

1,286,731.

Specification of Letters Patent.

Patented Dec. 3, 1918.

Application filed July 15, 1916. Serial No. 109,419.

To all whom it may concern:

Be it known that I, JOHN F. O'CONNOR, a citizen of the United States, residing at Chicago, in the county of Cook and State 5 of Illinois, have invented a certain new and useful Improvement in Detachable Draw-Bar and Yoke Connections, of which the following is a full, clear, concise, and exact description, reference being had to the accompanying drawings, forming a part of 10 this specification.

This invention relates to improvements in detachable draw bar and yoke connection.

One object of the invention is to provide 15 a yoke having a hood at its forward end, with a shiftable shouldered locking block mounted within the hood.

Another and more specific object of the invention is to provide a two-part yoke 20 which, when the parts are assembled, form a hollow hood at their forward ends to receive the draw bar butt, the hood having vertically slidably mounted therewithin, a shouldered locking block to coöperate with 25 the lower shoulder of the draw bar.

In the drawing forming a part of this specification, Figure 1 is a part longitudinal section, part side elevation of a draw bar and yoke showing my improvements in connection therewith. Fig. 2 is a horizontal sectional view of the structure illustrated in Fig. 1 and taken on the line 2—2 thereof. Fig. 3 is a front end elevation of the improved yoke shown in Fig. 1. Fig. 4 is a vertical, transverse section taken on the line 35 4—4 of Fig. 1. Fig. 5 is a perspective view of the improved locking block employed with the yoke. Fig. 6 is a detailed view 40 illustrating one of the yoke members and particularly the hinge forming connection thereon.

In the drawing, 10 denotes M. C. B. draw bar having usual upper and lower shoulders 45 11 and 12. The improved yoke A comprises two members 13 and 14, each of loop formation, the upper and lower arms of each of 50 said members being connected at their front ends by side plates 15—15. The member 13 is provided at its front end, on the top there- 55 of, with an inwardly extended hinge lug 16, the lug extending downwardly, and the member 14 is provided with a correspond- 60 ing hinge lug 17 which extends upwardly, the two lugs 16 and 17 forming a detachable 65 hinge joint by which the yoke parts are con- nected by swinging the same from a position 70 substantially end to end to a position where the parts are parallel. Each of the yoke members has the side plate 15 thereof 75 provided with a vertically extending recess 18 which is offset outwardly, an inwardly 80 extended lug 19, and another recess or groove 20 at the rear of the lug 19. When the two yoke members 13 and 14 are brought 85 into parallel position, they form a hood to receive the draw bar butt, and in the bottom 90 of said hood is provided a recess formed by the grooves 18 and 20 and the lugs 19 and within which is vertically slidably mounted 95 a locking block B. The latter consists of a front portion 21 which is slidable within the grooves 18, a rear portion 22 which is 100 slidable within the recesses 20, a central portion 23 of reduced width which is slidable between the lugs 19, and horizontally outwardly extended shoulders or ledges 24—24 105 which engage beneath said lugs 19 and limit the upward movement of the block. The portion 22 of the locking block is shouldered 110 on its under-face as indicated at 25 which shoulder coöperates with corresponding 115 horizontal shoulders or ledges 26 formed on the inner faces of the side plates of the yoke members. Said shoulders 26, as clearly appears from Fig. 1, limit the downward 120 movement of the locking block and prevent 125 the latter from dropping out of the yoke when the two parts of the latter are held in 130 operative position. The locking block B is 135 held up or in operative position by means of 140 a transverse, extending bolt 27 which passes 145 through suitable perforations in the side 150 walls 15 and through perforations 28 in the locking block. As will be understood, the 155 block B is placed between the two yoke parts 160 before the latter are swung to parallel position and hence when the yoke parts are 165 brought parallel to each other and held in 170 this condition, the block B is slidably mounted 175 in the lower portion of the hood and the 180 yoke A is limited in its up and down movements so that it cannot become displaced. 185 By removing the bolt 27, the block B can 190 be dropped down to its lowermost position 195 under which condition, the draw bar butt 200 may be inserted. When the latter is raised 205 so as to engage the transversely extending 210 gib 29 across the top of the hood, the block 215 B is then elevated and held in this elevated 220 position by inserting the bolt 21. As will 225

also be apparent, the block B bears against a number of suitable shoulders formed by the yoke parts, thus relieving the bolt 27 of strain due to pulling movements on the draw bar.

I claim:

1. A yoke having parallel arms and provided with means for engaging the upper shoulder of a draw bar butt, and a vertically adjustable shouldered block separate from said arms and mounted in the lower part of the yoke for engagement with the lower shoulder of a draw bar butt, and means for holding said block in elevated operative position.
2. A yoke having parallel arms and provided with a hooded forward end, means in the hooded end for engaging the upper shoulder of a draw bar butt, and a vertically adjustable shouldered block separate from said arms and mounted in the lower part of said hood and adapted to engage the lower shoulder of a draw bar butt, said yoke having means preventing removal of the block therefrom, and means for holding said block in operative position.
3. As an article of manufacture, a two-part yoke, the parts having means for preventing lateral separation thereof when operatively assembled, the parts also forming a hood at the forward end of the yoke with a recess in the bottom wall of the hood and a locking block mounted within said recess and adapted to engage the lower shoulder of a draw bar butt.
4. A yoke for draft riggings comprising two parts which, when assembled, form a hood at the forward end of the yoke adapt-

ed to receive a draw bar butt and the said parts having upper shoulders to engage the upper shoulder of a draw bar butt, said parts also forming, when assembled, a recess in the lower part of the hood and a locking block slidably mounted within said recess and adapted to engage the lower shoulder of a draw bar butt.

5. As an article of manufacture, a yoke for draft riggings comprising two parts detachably connected together and having a hood formed at their forward ends to receive a draw bar butt, the hood being provided with a recess in the bottom wall thereof, and a shouldered locking block vertically slidably mounted within said recess when the yoke parts are assembled.

6. As an article of manufacture, a yoke for draft riggings comprising two parts detachably connected together and having a hood formed at their forward ends to receive a draw bar butt, the hood being provided with a recess in the bottom wall thereof, and a shouldered locking block vertically slidably mounted within said recess when the yoke parts are assembled, the yoke parts and said block having coöperating shoulders limiting the up and down movement of the block relatively to the yoke to thereby prevent the block from being taken out when the yoke parts are assembled.

In witness that I claim the foregoing I have hereunto subscribed my name this 12th day of July 1916.

JOHN F. O'CONNOR.
